METHOD OF DESIGNATING TEMPERATURE ZONES IN ICEBOXES

Filed July 15, 1930

UNITED STATES PATENT OFFICE

BURRIS D. WOOD AND WILLIS WILLIAM RODGERS, OF DALLAS, TEXAS.

METHOD OF DESIGNATING TEMPERATURE ZONES IN ICEBOXES

Application filed July 15, 1930. Serial No. 468,078.

This invention relates to ice refrigeration and it has particular reference to a device and method, through the medium of which temperature, which usually varies in degree 5 at different locations in the ice box or refrigerator, may be indicated after having first determined the normal temperature at different levels or at different points within the boxes and the principal object of the invention resides in the provision of means which will plainly indicate to the user of the refrigerator or ice box, the most practicable degree of temperature for certain kinds and character of foodstuff to best keep and be 10 more effectively preserved at the specified degree of temperature.

Another object of the invention resides in the provision of markers of the character above referred to, capable of indicating the 20 various kinds of foods or the like, which should be placed on the shelves or racks bearing the markers according to the degree of frigidity required for their proper preservation.

Still another object of the invention resides in the provision of a tag or marker calculated to indicate, at a glance, the shelf or rack upon which to place certain foods which, because of their inherent natures, require a certain 25 exactness in temperature with respect to its degree of frigidity, to prevent the deterioration of such foods, either by placing them too far away or by placing them in too close proximity to the source of frigidity.

Broadly, the invention comprehends the provision of a simple and inexpensive means whereby a person of very limited experience can ascertain the proper locations or positions in a refrigerator or ice box in which to place edibles or other commodities, where 30 they will be properly preserved.

While the foregoing objects are paramount, other novel objects and salient features of the invention will become manifest 45 as the description proceeds, taken in connection with the annexed drawings wherein:

Figure 1 is a perspective view of a refrigerator or ice box showing the invention attached to the shelves therein and showing 50 the ice chamber.

Figure 2 is a detailed perspective view of one of the wire shelves showing the invention attached.

Figure 3 is an elevational view of the invention.

Figure 4 is an elevational view of a modification of the invention.

Figure 5 is the preferred type of clip used to apply the invention, and

Figure 6 is an end elevational view of the invention.

Some foods, such as milk, butter, salads and the like, because of their inherent tendencies to spoil or deteriorate quickly when not properly cooled must be carefully protected 65 against warmth and it is vitally necessary, therefore, to place them in a place where the lowest temperature can be obtained. When it is ascertained where the lowest temperature prevails, the invention can be attached to the 70 shelf for permanent reference.

Other foods, such as vegetables, cooked meats and the like, may be placed further away from the source of frigidity and therefore another of the markers may be placed 75 on an adjacent shelf located at a greater distance from the first.

Due to the different designs and arrangement of refrigerators, a lower temperature may be found in one at a position at the side 80 of the ice chamber or the source of frigidity while it may be near the top or at the bottom in another refrigerator and by testing the different locations with a thermometer or other device, a true and permanent marking 85 can be placed thereon.

Accordingly, the invention is comprised of a plate 1 of metal or other suitable material, having apertures 2 in the upper edge thereof through which a clip 3 is inserted which is 90 capable of being turned about or through the edge of a shelf 4, as shown in Figure 2, to secure the plate 1 against displacement. This clip 3 is shown in detail in Figure 5.

By reference to Figure 1, it will be seen that the shelves or racks 4 are placed in the refrigerator 5 in a separate compartment to that of the ice 6 so as to eliminate dampness and because the racks 4 differ in regard to their proximity to the ice chamber 7, the same de- 95 100

gree of frigidity cannot be obtained. In order, therefore, to obtain the best results, permanent identification should be placed upon the various racks 4 so that proper use can be made of them.

Since there are no racks 4, ordinarily, in the bottom of the compartments, it is necessary to attach the plates 1 to these by a different method and a modification, such as 10 shown in Figure 4 is provided which can be attached to the bottom of the compartments at *a*, as shown in Figure 1 by screws or nails.

With reference now to Figures 3 and 4, it is pointed out that the wording upon the 15 plates 1 is calculated not only to indicate the temperature at that location and the kinds of food to be placed upon the rack 4 to which the plate 1 is attached but indicates at *b* the name of the firm from whom ice may be purchased and therefore provides a desirable means of advertising for the dealer which is constantly before the customer whenever the refrigerator is opened.

Manifestly, the construction shown is capable of considerable modification and such modification as is considered within the scope and meaning of the appended claims is also considered within the spirit and intent of the invention.

30. What is claimed is:

1. The herein described method which consists initially in predetermining the varying degrees of temperature at different points in said ice box and in affixing a label at each of 35 said points designating the temperature and specifying the commodities best suited for the designated temperature.

2. The herein described method which consists initially in obtaining a check of the degrees of temperature at different points in 40 said ice boxes and in designating the normal temperature by visible means and in specifying the character of foodstuffs best preserved in the temperature designated.

45. In testimony whereof we affix our signatures.

WILLIS WILLIAM RODGERS.
BURRIS D. WOOD.
